(57) **CLAIM**

The ornamental design for a toddler's drinking straw, as shown and described.

DESCRIPTION

FIG. 1 is a top plan view of a toddler's drinking straw, with an aperture pointed to the right, showing my new design; FIG. 2 is a top plan view thereof, shown in an alternative position;

FIG. 3 is a left side elevation view;

FIG. 4 is a front elevation view;

FIG. 5 is a rear elevation view;

FIG. 6 is a right side elevation view;

FIG. 7 is a a front left perspective view thereof, shown in a first position;

FIG. 8 is a front right perspective view thereof, shown in a second position;

FIG. 9 is a side elevation view thereof, shown in environmental use; and,

FIG. 10 is a second front right perspective view thereof, shown in environmental use.

The broken lines showing the cup and lid in FIGS. 9 and 10 show the environment in which a toddler's drinking straw is used and forms no part of the claimed design.

1 Claim, 6 Drawing Sheets
